US00D368434S

United States Patent [19]

Dennewill et al.

[11] Patent Number: Des. 368,434

[45] Date of Patent: **Apr. 2, 1996

[54] CORNEAL TOPOGRAPHER

[75] Inventors: **James R. Dennewill**, Lakewood; **Pierre Boisier**, Laguna Hills; **David M. Domash**, Mission Viejo; **Donn D. Lobdell**, Corona Del Mar; **Paul C. Pynckel**, Santa Ana, all of Calif.; **Heather Ready**, Keller, Tex.; **David Weston**, Newport Beach, Calif.

[73] Assignee: **Alcon Laboratories, Inc.**, Fort Worth, Tex.

[**] Term: **14 Years**

[21] Appl. No.: **35,455**

[22] Filed: **Feb. 27, 1995**

[52] U.S. Cl. **D10/46**; D24/174

[58] Field of Search D10/46; D24/172; 351/206, 212, 237, 245
